UNITED STATES PATENT OFFICE.

THOMAS A. EDISON, JR., OF BURLINGTON, NEW JERSEY.

SUCTION-FEED.

1,389,425.

Specification of Letters Patent. Patented Aug. 30, 1921.

Application filed January 14, 1918. Serial No. 211,887.

To all whom it may concern:

Be it known that I, THOMAS A. EDISON, Jr., a citizen of the United States, residing at Burlington, in the county of Burlington 5 and State of New Jersey, and whose post-office address is Burlington, New Jersey, R. F. D. No. 3, have invented certain new and useful Improvements in Suction-Feeds, of which the following is a full, clear, and ex-

10 act description.

My invention relates to various new and useful improvements in suction feeds adapted particularly for use for the purpose of supplying gasoline or other liquid fuel to 15 a carbureter occupying a higher level than the tank and from which carbureter the explosive gas is delivered to an internal combustion engine. My improved feed operates on the suction principle, that is to say, by 20 suction developed at the intake side of the engine. I am, of course, aware that it has been proposed to utilize this suction for the purpose of drawing the fuel from the supply tank upwardly into the carbureter or into 25 an auxiliary tank from which the fuel may flow by gravity into the carbureter.

The object of my invention is to produce an improved suction feed of simple construction and of entirely certain and efficient 30 operation. In carrying my invention into effect I utilize a chamber or cylinder in which the gasoline or other liquid fuel will be drawn by suction and I employ a float or piston (as the case may be) which 35 rises with the liquid entering the chamber or cylinder, the construction being such that when the float or piston reaches the end of its upward movement the suction inlet to the chamber or cylinder will be suddenly 40 cut off and simultaneously the partial vacuum will be broken by permitting the entrance of atmospheric air, thus allowing the gasoline or other liquid fuel to flow through directly 45 into the carbureter by gravity or preferably to flow into an auxiliary tank. I will hereafter describe two ways by which the invention may be carried into effect.

With the first plan a chamber is used connected to the suction, having an auxiliary 50 tank below it and provided with a float in said chamber controlling a suction cut-off valve, whereby when the latter operates to suddenly cut off the suction and the partial vacuum is broken, the gasoline or other liquid fuel will be permitted to slowly pass

into the auxiliary tank or directly into the carbureter at a rate dependent upon the consumption, the operation being repeated when the float has reached its lowermost position and permitting the suction to be again 60 applied. With this form of device the operation of the parts is comparatively infrequent, especially if the engine is running slowly.

With the second and preferred form of the 65 invention, I make use of a cylinder in which works a piston controlling the suction cut-off valve. The arrangement is such that under the effect of suction the piston will rise in the cylinder drawing a charge of 70 gasoline into the cylinder from the supply tank. When the piston reaches its uppermost limit, the suction cut-off valve will operate and the partial vacuum will also be broken. Thereupon the piston will descend, 75 discharging the supply of gasoline into an auxiliary tank connected to the carbureter and near the end of its down stroke the piston will operate the suction cut-off valve to again cause the suction to elevate the piston. 80 With this arrangement the cylinder and piston practically constitute a gasoline pump, drawing charges of gasoline into the cylinder and discharging them into the auxiliary tank, the excess supply of gasoline 85 in the auxiliary tank overflowing back to the main gasoline tank, and the operation therefore is continuous so long as the engine operates.

In order that my invention may be better 90 understood, attention is directed to the accompanying drawings forming a part of this specification, and in which—

Figure 1 is a general diagrammatic view 95 of the preferred embodiment of my invention, showing the relation of the vacuum pump and auxiliary tank to the carbureter and main tank.

Fig. 2 a longitudinal sectional view on an enlarged scale of the vacuum pump and auxiliary tank showing the parts in the position they occupy when the piston is moving upward.

Fig. 3, a similar view showing the suction cut-off valve closed and the air valve opened, 105 the piston being near the end of its downward stroke, the continuation of which stroke will open the suction cut-off valve; and

Fig. 4 an enlarged longitudinal sectional 110

view of a modification, in which a chamber pipe 5, as shown, or to the main tank 1, and and float are used, showing the float on its upward stroke.

In all of the above views, corresponding parts are represented by the same numerals of reference.

The main fuel tank 1 of any suitable construction is shown as being on a slightly lower level than the carbureter 2. The 10 vacuum pump comprises a cylinder 3 in which is mounted a light piston 4 sliding freely therein. A pipe 5 leads from the main tank 1 into the lower end of the cylinder 3 and is provided with a check valve 6 of any suitable type to permit the gasoline to flow freely into the cylinder but preventing a return flow thereof in the usual way. A pipe 7 leads from the intake pipe 8 of the carbureter or is otherwise connected to 15 the suction, to the top of the cylinder as shown so as to permit suction to be developed within the cylinder as will be understood. The suction inlet to the cylinder is formed with an enlarged bore 9 which constitutes a small auxiliary cylinder as will be 20 presently described.

Coöperating with this auxiliary cylinder is a plug or secondary piston 10, the upper end of which is conical as shown, and which 25 constitutes the suction cut-off valve by co-operating with the seat formed at the upper face of the auxiliary cylinder 9. The plug or secondary piston 10 fits the auxiliary cylinder with a fairly close fit so as to travel 30 freely therein. The plug 10 is provided with a stem 11 having a head 12 at its lower end which head works in a tube 13 carried by the piston 4 and provided at its upper end with a plate 14 having an opening therein 35 through which the stem 11 freely slides. The stem 11 and tube 13 are properly proportioned as to length to provide for the effective stroke of the piston 4, as will be understood. Carried by the plug or sec- 40 ondary piston 10 at the bottom is a flange 15 adapted to engage the stem 16 of a valve 17 which permits atmospheric air to enter the cylinder simultaneously with the cut-off of the suction as will be explained. Secured 45 to the bottom of the cylinder 3 is a small auxiliary tank 18, having an air vent 19 therein, permitting gasoline to freely flow therefrom into the carbureter through the openings 20 and pipe 21. A light check 50 valve 22 comprising a disk coöperating with the seat 23 is arranged between the auxiliary tank 18 and the cylinder 3, so as to close on the up stroke of the piston. This check valve may be provided with a stem 24 55 with which the piston 4 may engage when it drops entirely down in case the engine stops running, so that all of the gasoline from the cylinder 3 will flow into the auxiliary tank 18.

Extending into the auxiliary tank 18 is an 60 overflow pipe 25 which leads back to the

through which excess gasoline flows out of the auxiliary tank. In operation it will be seen that when the engine is started, suction will be created at the intake pipe 8 causing 70 the carbureter to operate in the usual way. This suction in the pipe 7 will be created in the cylinder 3 above the piston, the air valve 17 being closed. Consequently the piston 4 will rise drawing a charge of gasoline from the tank 1 into the cylinder 3, the check valve 6 opening in this movement and the check valve 22 being closed. As soon as or shortly after the plug or secondary piston 10 enters the auxiliary cylinder 9, the suction 75 will cause the plug to be drawn rapidly upward to close the suction cut-off valve as shown in Fig. 3, and the suction will keep this valve closed until it is forcibly opened as will be explained.

Just as the suction cut-off valve is about to close, the flange 15 will strike the stem 16 of the air valve and open the air valve 17 permitting atmospheric air to enter the cylinder and break the partial vacuum. The 80 weight of the gasoline in the cylinder 3 and the weight of the piston 4 will thereupon cause the piston to descend and the gasoline will flow past the check valve 22 into the auxiliary tank 18. The piston 4 descends 85 until the plate 14 of the tube 13 engages the head 12 as shown in Fig. 3 and its further descent will forcibly withdraw the plug 10 from its seat and permit the plug to drop down to the position shown in Fig. 2, thus 90 allowing the air vent to close. Thereupon suction being again created in the cylinder 3 the operation described will be repeated. In this way charges of gasoline will by the 95 vacuum pump be continuously drawn (so 105 long as the engine operates) from the main tank 1 and discharged into the auxiliary tank 18, any overflow from said tank flowing back to the main tank and thus there will always be a supply of gasoline to flow from 110 the auxiliary tank to the carbureter. It will be understood that with the device described the operation of the vacuum pump proceeds 115 continuously so long as the engine operates and being independent of the amount of gasoline consumed by the engine.

Referring to Fig. 4, I illustrate a modification of the invention in which the operation is irregularly intermittent, that is to say, is dependent upon the rate at which the gasoline is used. With this modification I show a chamber 26 formed with an auxiliary tank or smaller chamber 27 at its bottom from which the pipe 21 leads to the carbureter. With this modification the air vent comprises a pipe 19' running up the outside of the chamber 26. Between the chamber 26 and the auxiliary chamber 27 is a check valve 28 permitting gasoline to flow downwardly but preventing its flow upwardly. 130

Leading into the chamber 26 near its bottom is the pipe 5 having check valve 6 as with the arrangement shown in Fig. 2. The suction pipe 7 leads to the upper part of the chamber 26 and is provided with an auxiliary cylinder 9 as with the arrangement of Fig. 2. With this form also the same air valve 17 is used with stem 16. Also the plug or secondary piston 10 is the same and operates in the same way with the auxiliary cylinder 9. Likewise the plug 10 is provided with a flange 15 coöperating with the air vent 17. With this modification the tube 13 is carried by a hollow float 29, the plate 14 being carried by the float and functioning in the same way with the head 12 when the suction cut-off valve is to be operated. In this modification the stem 11 works in a suitable guide 30, supported by a bracket 31, 20 as will be understood.

With the modified arrangement referred to, the suction created in the chamber 26 will draw a charge of gasolene from the fuel tank 1 through the pipe 5, the check valve 28 closing during this suction stroke. As the float rises it carries the plug 10 upward until the plug finally enters the auxiliary cylinder whereupon the suction suddenly snaps it upward to cut off the suction supply and open the air vent 17. Thereupon air may enter the chamber so long as the suction cut-off valve is held by suction in contact with its seat. Therefore the supply of gasolene in the chamber 26 slowly flows downward, according to the rate of consumption in the carburetor and the float likewise descends until the head 12 is engaged with the plate 14 so as to unseat the suction cut-off valve and permit it to drop in position shown in Fig. 4, simultaneously closing the air vent. Thereupon suction being again created within the chamber 26 a succeeding supply of gasolene from the tank 1 will be drawn into the chamber 26 and the operations described will be repeated. In the drawing, an internal combustion engine of typical form is indicated at 32, connected to the intake pipe 8 of the carburetor.

Having now described my invention, what I claim as new therein and desire to secure by Letters Patent is as follows:—

1. In suction feeds for liquid fuel, the combination of a fuel tank or receptacle into which successive charges of the liquid fuel are to be drawn by the suction of the engine, and means actuated by suction whose action is determined by the height of the liquid in the receptacle for entirely cutting off the suction with a snap-action and breaking the partial vacuum to allow the charge to recede, substantially as set forth.

2. In suction feeds for liquid fuel, the combination of a fuel tank or receptacle into which successive charges of liquid fuel are to be drawn by the suction of the engine, an

element whose position is determined by the height of the liquid in the receptacle, a suction cut-off valve carried by said element and actuated by suction for entirely cutting off the suction with a snap-action when a full charge has entered the receptacle, and means controlled by said element for simultaneously breaking the partial vacuum to allow the charge to recede, substantially as set forth. 75

3. In suction feeds for liquid fuel, the combination of a fuel tank or receptacle into which successive charges of the liquid fuel are to be drawn by the suction of the engine, an element whose position is determined by the height of the liquid in the receptacle, a suction cut-off valve carried by said element and actuated by suction for entirely cutting off the suction with a snap-action when a full charge has entered the receptacle and an air valve operated by said element for simultaneously breaking the partial vacuum to allow the charge to recede, substantially as set forth. 85

4. In suction feeds for liquid fuel, the combination of a fuel tank or receptacle into which successive charges of the liquid fuel are to be drawn by the suction of the engine, an element whose position is determined by the height of the liquid in the receptacle, a suction cut-off valve carried by said element for entirely cutting off the suction with a snap-action when a full charge has entered the receptacle, means controlled by said element for simultaneously breaking the partial vacuum to allow the charge to recede, and means controlled by said element in its lower position for withdrawing the suction cut-off valve and restoring suction conditions in the receptacle, substantially as set forth. 90 100 105

5. In suction feeds for liquid fuel, the combination with an internal combustion engine and a fuel tank, of a reciprocating vacuum pump operated by the suction of the engine for continuously withdrawing successive charges of liquid fuel from said tank at a rate independent of the consumption of such fuel by and speed of the engine, substantially as set forth. 110

6. In suction feeds for liquid fuel, the combination with an internal combustion engine, a fuel tank and an auxiliary tank, of a reciprocating vacuum pump operated by the suction of the engine for continuously withdrawing successive charges of the liquid fuel from the fuel tank and discharging the same into the auxiliary tank at a rate independent of the consumption of such fuel by and speed of the engine and an overflow from the auxiliary tank for accommodating the surplus liquid fuel supplied therein, substantially as set forth. 115 120 125

7. In suction feeds for liquid fuel, the combination with an internal combustion engine, a fuel tank and an auxiliary tank, of a re- 130

- 5 ciprocating vacuum pump operated by the suction of the engine for continuously withdrawing successive charges of the liquid fuel from the fuel tank and discharging the same into the auxiliary tank at a rate independent of the consumption of such fuel by and speed of the engine, said vacuum pump comprising a cylinder and means whose action is determined by the height of the liquid
- 10 5 therein for cutting off the suction and breaking the partial vacuum to allow the charge to recede, substantially as set forth.
8. In suction feeds for liquid fuel, the combination with an internal combustion engine and a fuel tank, of a reciprocating vacuum pump operated by the suction of the engine for continuously withdrawing successive charges of liquid fuel from said tank at a rate independent of the consumption of such
- 15 10 fuel by and speed of the engine, said vacuum pump comprising a cylinder, a piston therein whose position is determined by the height of the liquid in the cylinder, a suction cut-off valve carried by said piston for cutting
- 20 15 off the suction when a full charge has entered the cylinder, and means controlled by said piston for simultaneously breaking the partial vacuum to allow the charge to recede, substantially as set forth.
- 25 20 9. In suction feeds for liquid fuel, the combination with an internal combustion engine and a fuel tank, of a reciprocating vacuum pump operated by the suction of the engine for continuously withdrawing successive
- 30 25 charges of liquid fuel from said tank at a rate independent of the consumption of such fuel by and speed of the engine, said vacuum pump comprising a cylinder, a piston therein whose position is determined by the height
- 35 30 of the liquid in the cylinder, a suction cut-off valve carried by said piston for cutting off the suction when a full charge has entered the cylinder and an air valve operated by said piston for simultaneously breaking the
- 40 35 partial vacuum to allow the charge to recede, substantially as set forth.
- 45 40 10. In suction feeds for liquid fuel, the combination with an internal combustion engine and a fuel tank, of a vacuum pump
- 50 45 operated by the suction of the engine for continuously withdrawing charges of liquid from said tank at a rate independent of the consumption of such fuel by the engine, said pump comprising a cylinder, a piston therein
- 55 50 whose position is determined by the height of the liquid in the receptacle, an auxiliary cylinder, a secondary piston or plug coöperating therewith carried by the main piston and constituting a suction cut-off valve
- 60 55 for cutting off the suction when a full charge has entered the cylinder, and means controlled by said main piston for simultaneously breaking the partial vacuum to allow the charge to recede, substantially as set
- 65 60 forth.
11. In suction feeds for liquid fuel, the combination with an internal combustion engine, a fuel tank and an auxiliary tank, of a reciprocating vacuum pump operated by the suction of the engine for continuously withdrawing successive charges of the liquid fuel from the fuel tank and discharging the same into the auxiliary tank at a rate independent of the consumption of such fuel by and speed of the engine, said vacuum pump comprising a cylinder and piston, a suction cut-off valve whose action is determined by the height of the liquid in the cylinder for cutting off the suction and breaking the partial vacuum to allow the charge to recede, and means controlled by said piston in its lower position for withdrawing the suction cut-off valve and restoring suction conditions in the cylinder, substantially as set forth. 70
12. In suction feeds for liquid fuel, the combination with an internal combustion engine and a fuel tank, of a vacuum pump operated by the suction of the engine for continuously withdrawing charges of liquid from said tank at a rate independent of the consumption of such fuel by the engine, said pump comprising a cylinder, a piston therein whose position is determined by the height of the liquid in the cylinder, an auxiliary cylinder, a secondary piston or plug coöperating therewith carried by the main piston and constituting a suction cut-off valve for cutting off the suction when a full charge has entered the receptacle, means controlled by said main piston for simultaneously breaking the partial vacuum to allow the charge to recede, and means controlled by said main piston in its lower position for withdrawing the suction cut-off valve and restoring suction conditions in the cylinder, substantially as set forth. 80
13. In suction feeds for liquid fuel, the combination with an internal combustion engine, a fuel tank and an auxiliary tank, of a reciprocating vacuum pump operated by the suction of the engine for continuously withdrawing successive charges of the liquid fuel and discharging the same into the auxiliary tank at a rate independent of the consumption of such fuel by and speed of the engine, said pump comprising a cylinder and piston whose action is determined by the height of the liquid therein for cutting off the suction and breaking the partial vacuum to allow the charge to recede, and an overflow from the auxiliary tank for accommodating the surplus liquid fuel supplied thereto, substantially as set forth. 90
